UNITED STATES PATENT OFFICE.

JACOB J. REUSCH, OF ST. PAUL, MINNESOTA, ASSIGNOR TO NATIONAL SIGN STENCIL COMPANY, OF ST. PAUL, MINNESOTA, A CORPORATION.

STENCILING DEVICE.

Application filed March 2, 1923. Serial No. 622,300.

To all whom it may concern:

Be it known that I, JACOB J. REUSCH, a citizen of the United States, residing at St. Paul, in the county of Ramsey and State of Minnesota, have invented a new and useful Improvement in Stenciling Devices, of which the following is a specification.

My invention relates to a stenciling device wherein it is desired to provide a complete unit including a series of stencils which may be arranged in a compact form.

The invention further includes a suitable means for clamping the card upon which the sign is being stenciled in a manner so that a suitable sign can be made up with a very neat and attractive appearance. A feature of the invention resides in means which are adaptable to various sizes of signs so that, within a certain range of dimensions, a large variety of signs and styles can be produced by my stenciling device.

The stenciling device is provided with a series of gauges or scales by which the card to be stenciled can be properly positioned within the clamping means and a gauge or scale is provided which permits the operator to readily judge how far the stencil is moved each time a letter is stenciled on the card upon which the sign is being made. This means is particularly adapted to the segmental stencils which are used in my device and which permit a wider range and variety of signs to be made.

The invention includes suitable indicia on each stencil which indicates the distance that the stencil is to be moved between each letter, in stenciling a word, together with additional indicia to indicate the number of letters in a word or series of words. This indicia on the stencil, in combination with the scale upon the clamping member of the stenciling device all function together to permit an unskilled person to stencil a sign with the precision and accuracy of an expert.

In the drawings forming a part of this specification:

Figure 1 is a front perspective view of the invention as it would appear in use.

Figure 2 is a plan view of the stenciling apparatus with the stencil holding tray removed.

Figure 3 is a vertical cross section of the

same, a portion of which is indicated in dotted lines and broken away.

55

Figure 4 is a view of one of the stencils.

Figure 5 is another view of the other side of the stencil.

Figure 6 is a perspective view of the apparatus illustrating another form of arrangement of the indicating scales.

60

A feature of the invention resides in providing a uniform scale upon the cabinet, or the clamp of the cabinet, which holds the card, that is being stenciled, which indicates the distance that the stencil should be moved between each letter in the making of a sign. Each stencil is provided with indicia, such as one-eighth, one-fourth, or the like indicating spaces indicated on the scale on the clamp so that the proper space is in evidence on each stencil to provide a uniform distance between the letters.

65

The indicia on the stencil also includes a scale from "one" up which indicates the number of letters in a word or a series of words which it is desired to stencil unto the card in a single line. This scale is proportioned in proper relation to the first named indicia on the scale which indicates the spaces between letters, so that, if that particular space is used between each letter then by following the scale which indicates from "one" up, such as just mentioned, the letters can be properly spaced even by an amateur so that the sign is equally proportioned on the card from the center thereof to place the letters of the words at proper relation from the center of the card.

75

If the word "Candles", which includes seven letters, were to be stenciled on a card then the stencil having the proper sized letters would be selected and turned to the scale or indicia which indicates the number of letters in the word and the edge of the card would be held at the center of the sheet, while a slight pencil mark would be made directly below the numeral "7". This would indicate the point to start the word "Candles" and when this word had been

80

stenciled unto the card by using the space indicated on the stencil between the letters, it would be found that the word would be properly spaced with its letters extending equally on either side of the center line indicated on the stencil apparatus and card.

100

105

The drawings illustrate my stenciling apparatus A which is formed of any suitable material and is provided with a body portion B which is formed with a flat work table 10 on the front upper side and an opening or recess 11 which is adapted to receive the drawer C.

- 5 table 10 on the front upper side and an opening or recess 11 which is adapted to receive the drawer C.
- 10 The body portion upon which the work table 10 is formed is provided with a holding clamp 12 which extends across the same and is arranged to hold the clamping member 12 into engaging position by means of the cam levers 14 which are positioned at either end of the clamp. These members 15 are of ordinary construction and the cam surfaces of which engage against the top of the work table to elevate the engaging edge 15 of the clamp off the surface of the table 10.
- 20 Directly in back of the clamp 12, elevated above the table surface, is an ink or color holding tray 16 which is divided into several compartments so as to receive the color cakes 17 and 18, while a compartment in the center 25 is formed which is suitable for holding the stenciling brush 19. On either side of the color cakes are positioned and firmly held moisture jars. These jars are held by the recess 21 formed in the compartment adjacent the color cakes. It is essential 30 that the moisture jars 20 be held firmly in place while in use so that the stencil brush 19 can be readily inserted within the same for moisture before it is applied to the color cake.

In providing means for holding the moisture jars 20 firmly in place while in use, the operator can use both hands, one to hold the stencil and one to operate the stenciling brush. Yet the moisture jars are removed from the recess 21 so that they can be stored away within the drawer C when not desired for use.

40 The drawer C is formed with a central stenciling compartment 22 in which the stencils 23 are arranged in suitable order with the smaller stencils in the bottom and increasing toward the top. This arrangement permits various size letters to be held 45 compactly within the compartment 22 in an ordinary manner readily accessible for use.

50 The stenciling device A is formed with a backwardly inclined shelf 24 and a pair 55 of engaging members 25 are secured to either end of the shelf which are adapted to engage the projecting tongues 26 formed on the front of the drawer C and which project from either end of the same. These 60 tongues 26 hold the drawer C in a backward inclined position extending upward so that the compartment 22 is readily accessible to the operator with the upper edges of the stencil compartments in view 65 so that the desired stencil can be selected.

The drawer C is formed so that compartments 28 are formed at either end of the compartment 22 and a compartment 29 is formed along the back or upper side of the drawer C when the same is positioned extending upward from the body portion B. These compartments form suitable space for holding the moisture jars 20 and the stenciling brush 19 together with any other articles which may be used in connection with the making 70 of signs by means of the stenciling apparatus. It is desirable, to have compartments for storage of articles of this nature so that the entire stenciling device can be compactly arranged together and stored away when 75 not desired for use.

If the stencils are formed with segmental letters 30, as illustrated in figures 4 and 5, these segmental letters are made only of such letters of the alphabet as can be readily 80 divided and by thus forming the stencil, fewer letters are necessary because the same characters can be combined to make these letters. This construction reduces the number of structures and provides a suitable 85 means for spacing the letters from each other. Each stencil is provided with indicating marks 31 along the longitudinal edges and adjacent these indicating marks is positioned indicia 32 to indicate either 90 portion of an inch or a suitable scale which is used in conjunction with the scale 33 extending along the engaging edge 15 of the clamp 12 so as to indicate the distance or 95 space between each letter for that particular 100 stencil.

In addition to the indicia, each of the stencils are provided with indicia 34 which may consist of numerals properly spaced apart extending from the right hand edge 105 35 and along one side of the stencil, as indicated in Figure 5. This indicia indicate the number of letters in a word or a series of words which are to constitute a line desired 110 to be stenciled unto a card held in the clamp 12. These numbers or this indicia indicating the number of letters desired for use are properly spaced apart in proportion, to the indicia indicating the distance adapted for 115 use between each letter, as indicated by 32 and are so arranged to divide the space exactly in half required for the letters which 120 are to be used to make up the line on the card.

To center the sign on the card to be stenciled so that the same number of letters will appear on either side of the center of the same, the number of letters in the line to be stenciled are counted and then, by holding the edge 35 at the center of the card and counting off the number of letters in the word or line on the indicia 34 and placing a mark on the card at this point, the position to start the first letter of the word or line will be indicated so that the operator 130

can place the beginning of the first letter at this point and know that when he has finished the word or line the letters will be equally divided on either side of the center 5 of the card.

The work table A is flat and extends across the top of the entire body portion B with a clear space extending below the tray 16 and the shelf 24. This permits a card 10 D to be clamped or engaged by the clamp 12 on the table 10.

Before the card D is positioned on the table it is desirable to locate the center of the same, so that the sign can be neatly stenciled 15 upon the card.

The clamping member 12 is provided with an arrow 36 which indicates the center of the clamping member and is positioned before the center of the card D. To determine the center of the card D, a scale 37 20 which will indicate inches or other suitable spaces is formed or imprinted on the surface of the table 10. The card D is placed upon this scale which may begin at one edge 25 of the table 10, as indicated in Figure 2, and mesh together the overall width or dimension. A second scale 38 is provided which is divided into spaces which is half the spaces indicated by the scale 37 and is positioned adjacent the scale 37 extending 30 or starting from the center of the table 10, as indicated by the arrow 31.

By measuring the card D on the scale 37 and then raising the clamping member 12, 35 it can be slid freely along beneath the clamp and positioned so that the right hand edge will be positioned directly at the number on the scale 38 indicating the overall dimension as indicated by the scale 37 so as to position 40 the card D centrally on the table 10.

By means of a scale member E which is slidably held by the engaging springs 39 which engage the bevel surfaces 40 and 41 formed on the outer front edge of the table 45 10, along groove under the engaging edge of clamp 12 until it engages the edge 43 whereupon clamp 12 can be released into engaging position and the scaling member E can be moved to one side or removed entirely 50 from the work table 10. The scaling member E carries a scale 44 which indicates the sizes of letters of the respective stencils to indicate the height of the same so that the operator can readily judge the size of letters 55 he desires to use in stenciling a design.

When the card D is properly positioned with its center at the point of the arrow 36, then the desired stencil is selected by means of the indicia 34 on the stencil, a mark can 60 be placed upon the card to indicate the starting point for the first letter of the word selected to be stenciled. Just as is indicated in Figure 2, the word "Candles" includes seven letters and thus the scale or indicia 65 34 would be positioned with the edge of the

scale 35 at the center or in line with the arrow 31 while a mark would be placed directly below and in line with the numeral seven of the indicia 34 on the stencil. This will position the letters properly on either 70 side of the center line so that the word "Candles" can be stenciled in a neat and attractive manner upon the card D.

The scale 33 cooperates with the indicia 32 and the indicating marks on each of the stencils so as to properly space each letter 75 apart. This permits an amateur to make a very accurate sign by use of my stenciling device and includes an essential feature of the invention. With such a scale and the indicia 80 upon the stencils, it is necessary for the operator to approximate the distance between each letter and, if the operator is not careful in doing this, some letters will be spaced much farther apart than others 85 and the sign will not appear well after it is finished.

In the drawings, Figure 6 illustrates the clamping member 12 with the scales 33, 37 and 38 all arranged and combined so that 90 the scale 45 extending along the top of the bevelled edge of the clamping member would constitute the scales 33 and 37, which are similar in the other drawings, while the scale 46 would constitute the scale 38 to give the center division of the card D to be clamped unto work table 10. In this construction, the scales are removed from the surface of the work table 10 and arranged 100 on the clamping member 12, where these scales perform the desired function to cooperate with the scales to space the letters the proper distance apart and to divide the card centrally so as to properly space and position the sign on the same.

The invention includes the arrangement of the moisture holding means adjacent the color cakes together with the compact arrangement of the stencils in the drawer C which cooperate with the scale means by being held in accessible position so that the desired stencil can be brought into use quickly and gauged accurately by the scales to stencil a sign on a card in a neat and precise manner which can be readily accomplished by the arrangement set forth in the drawings by an unskilled person. This arrangement and positioning of the parts of my stenciling device permits the operator to use both hands in manipulating both the stencil and the stenciling brush which increases the accuracy of the sign and reduces the amount of the time necessary to make the same.

The drawings illustrate a particular form and construction of the device with a particular arrangement of the parts which I desire to have it understood are only illustrative and the invention can be carried out by other means and applied to other uses 125 130

than those set forth within the scope of the following claims.

I claim:

1. A stenciling device including a series 5 of stencils, means for holding said stencils in a concealed or display position, a stenciling table, a clamping means having a central point, a series of scales adapted to indicate the overall dimension of a card to 10 be stenciled upon and to indicate the center of the card and to indicate the movement of the stencil whereby a display can be stenciled equally spaced on either side of the center of the card held in said clamp, 15 a tray positioned in back and above said clamping device having a backwardly inclined shelf, whereby a card may be passed over said stenciling table through said clamping means and beneath said tray while 20 being stenciled.
2. A stenciling device including means for holding, concealed or displayed a series of stencils, a stenciling table, a squaring member adapted to position a card upon the device, means for holding said squaring member from free movement, means for rigidly holding the card in place, said means comprising a longitudinally positioned scale clamp pivotally mounted above the surface 25 of the stenciling table, a central indicating means carried by said longitudinal clamp adapted to indicate the center of the card to be stenciled on and scale means associated therewith whereby the card can be measured 30 and positioned centrally as indicated by said centering point to permit the configuration to be stenciled unto the card extending equally from either side of the horizontal line of the card, and a tray positioned in 35 back and above said clamp.

3. A stenciling apparatus including a clamping member adapted to form a horizontal straight edge, a T square member slidably arranged at right angles in relation to the horizontal edge of said clamping member, means for holding said T square against free movement to permit a card to be squared against the vertical edge thereof and to be clamped by said clamp and a series of scales associated with said clamp and T square to indicate on a card held in said clamp the central position of the card, the vertical height of letters to be stenciled on the card and the space that the letters of the stencil are to be spaced to make a uniform display with the letters equally spaced apart and centrally positioned upon the card being stenciled, and a tray positioned in back and above said clamp having a backwardly inclined shelf. 45 50 55 60

4. A stencil apparatus including a stenciling table, a scale for measuring the overall of a card to be stenciled on said table, a scale associated with said measuring scale having its starting point positioned centrally on said stenciling table adapted to indicate the central division measured by said measuring scale, a clamp for holding the card to be stenciled, indicating means on said clamp to indicate the center thereof and said indicating means being positioned in line with the point of the beginning of the scale associated with said measuring scale, a scale adapted to indicate the movement of the stencil between each letter in the stenciling of a sign and a tray positioned in back and above said clamp having a backwardly inclined shelf. 65 70 75

JACOB J. REUSCH.
